UNITED STATES PATENT OFFICE.

HERMAN H. OTTO AND HENRY A. OTTO, OF ROCHESTER, NEW YORK.

MATCH SCRATCHER FOR GARMENTS.

Application filed September 25, 1922. Serial No. 590,291.

To all whom it may concern:

Be it known that we, HERMAN H. OTTO and HENRY A. OTTO, both of Rochester, in the county of Monroe and State of New York, have invented certain new and useful Improvements in Match Scratchers for Garments; and we do hereby declare the following to be a full, clear, and exact description of the same, reference being had 10 to the accompanying drawing, forming a part of this specification, and to the reference numerals marked thereon.

Our present invention relates to clothing and, more particularly, to outer garments such as men's coats, vests and overcoats, and it has for its object to provide apparel of this general character with a neat, safe and efficient means whereby matches may be conveniently struck by the wearer without 20 injury to the garment. The improvements are directed in part toward providing a scratcher which will normally be protected against contact with other elements of the clothing, and which will not be bulky or 25 readily noticeable from either the interior or exterior of the garment. To these and other ends the invention consists in certain improvements and combinations of parts, all as will be hereinafter more fully described, 30 the novel features being pointed out in the claims at the end of the specification.

In the drawings:

Figure 1 is a fragmentary elevation of the interior of a coat provided with a match 35 scratcher constructed in accordance with and illustrating one embodiment of our invention;

Figure 2 is an enlarged view of a portion of the showing of Figure 1 in the immediate 40 vicinity of the match scratcher showing the latter in its normal position;

Figure 3 is a view similar to Figure 2 but showing the scratcher ready for use, and

Figure 4 is an enlarged section on the line 45 4—4 of Figure 1.

Similar reference numerals throughout the several views indicate the same parts.

As before indicated our match scratcher attachment is applicable to a variety 50 of outer garments in various positions thereon, but we have illustrated it in the present instance as applied to a man's sack coat in such position that he may hold the coat fairly taut at the front edge or lapel with 55 one hand and scratch the match with the other. Figure 1 shows the interior of the

coat in such a position wherein 1 indicates the facing having the buttonhole 2, and 3 indicates the lining stitched to the facing along the seam 4.

In the practice of our invention in its present preferred form we attach to the facing near the seam 4 and at a convenient height on the coat a flexible abrasive panel 5. This panel may be constituted by a piece 65 of ordinary emery cloth embodying a thin flexible fabric body coated, by means of an adhesive or otherwise, with emery, powdered glass or other of the abrasive crystals. It is held in place by stitches 6 at its edges 70 which cause it to lie closely and neatly against the facing and to bend or fold readily with the material of the garment. The panel is normally covered in the manner shown in Figures 1, 2 and 4 by a flap 75 7 which may be double faced to give it sufficient body and stiffness and which is preferably composed of the same material as the outer portion 8 of the garment and the facing 1. It is secured at its rear edge 80 at one side of the panel 5 so that its free edge extends forwardly as shown to conceal the panel though it may be swung or folded back rearwardly as in Figure 3 to give access to the panel in striking the 85 match. We prefer to secure the flap 7 by stitching into the seam 4 so that the facing, flap and lining are all attached together along the one seam line. Aside from the saving in operation this makes the facing 90 appear continuous, the flap being of the same material as aforesaid and normally lying close against it with the panel concealed.

The flap 7 not only protects undergarments from the abrasive effect of the panel 5 and from contact with materials from the match heads that may adhere to the panel, but it also, in the position of Figure 3, acts as a shield while the match is actually being 100 struck.

Our device being of the same flexibility throughout as the garment itself and being extremely light it does not interfere in any way with the hang or set of the coat 105 or bulge or project in any manner to indicate its presence from the exterior.

We claim as our invention:

1. In a match scratcher for wearing apparel, the combination with an outer garment having an inner facing at the front thereof, and a lining stitched to said facing,

of a flexible, abrasive panel secured to the facing near the seam of the latter and the lining and a protective flap for the panel secured in said seam.

- 5 2. In a match scratcher for wearing apparel, the combination with an outer garment having an inner facing at the front thereof, and a lining stitched to said facing of a flexible, abrasive panel composed of a fabric coated with abrasive and secured to the facing near the seam of the latter and the lining by means of stitches around the edges of the panel, and a protective flap for the latter secured in said seam.
- 10 15 3. In a match scratcher for wearing apparel, the combination with an outer gar-

ment, of a flexible abrasive panel secured to the inner side thereof, and a protective flap for the panel secured to the garment at one side of the latter.

- 20 4. In a match scratcher for wearing apparel, the combination with an outer garment, of a flexible abrasive panel secured to the inner side thereof and a protective flap of non-abrasive flexible material normally covering the panel and secured to the garment near the rear edge of the latter so that the free edge of said flap will project forwardly.

HERMAN H. OTTO.
